HAIR WAVING DEVICE

Filed April 4, 1928

FIG. 1

FIG. 3

FIG. 2

INVENTOR
A. W. CULVER
BY J. F. Cook
ATTORNEY

UNITED STATES PATENT OFFICE.

ALICE W. CULVER, OF HAMPTON PARK, MISSOURI.

HAIR-WAVING DEVICE.

Application filed April 4, 1928. Serial No. 267,146.

This invention relates generally to hair-waving devices and particularly to an improved hair-waving device adapted to be fitted to a person's head to place waves in the hair of said person, the predominant object of the invention being to produce a simple device of this type which is relatively light in weight and free from bulky parts whereby same may be worn without 10 discomfort while the user is asleep.

Fig. 1 is a perspective of my improved hair-waving device looking toward the front thereof, and showing the same as it will appear when in use.

15 Fig. 2 is a view similar to Fig. 1, but looking toward the rear portion of the device.

Fig. 3 is a perspective of a fragment of the device illustrating the manner in which the combs are attached to the head-fitting 20 appliance of the device.

In the drawing, which illustrates one embodiment merely of the invention, A designates my improved hair-waving device which comprises an appliance B adapted to be fitted upon the head of the user of the device, to which appliance is attached a plurality of combs C. The appliance B comprises a rear element 1 which, when the device is in use, is located at the rear of the 25 head of the person using the device. The rear element 1 may be formed of various materials which may be found to be suitable. However, I prefer to form this element of 30 fabric.

35 Extended downwardly from the rear element 1 is a pair of strips of suitable elastic material 2, said strips of elastic material being secured at their upper ends by stitching or otherwise to the rear element 1. At 40 their lower ends the strips of elastic material 2 are secured by stitches or otherwise to a strip of fabric or ribbon 3, which is arranged to encircle the neck of the wearer of the device in the manner illustrated in Figs. 1 and 2, said strip of fabric or ribbon being 45 capable of being drawn about the neck of the user of the device in a manner to permit the end portions thereof to be tied at the throat, as shown in Fig. 1. 4 designates a 50 strip of elastic material, designated herein as

a face strip, which is secured at one of its ends to the strip of fabric or ribbon 3 at a point thereon which is at a side of the neck of the wearer of the device when the same is in use. When the device is in use, the face 55 strip 4 extends upwardly along a side of the face of the wearer and curves over an eye, as shown in Fig. 1, said strip then extending across the forehead, at the approximate center of which the free end of said 60 strip is located.

5 designates a strip of elastic material which is similar to the strip 4, said strip 5 being secured to the strip of fabric or ribbon 3 at a point thereon which is located at 65 the opposite side of the wearer's neck to that at which the lower end of the strip 4 is secured to said ribbon, and said strip 5, which is also designated herein as a face strip, being extended upwardly along a 70 side of the face of the wearer and across the forehead to the approximate center thereof. The face strip 5 is provided with a hook 6 (Fig. 1) at the end thereof which is located at the center of the wearer's forehead, which hook is adapted to engage a suitable eye 6' arranged at the adjacent end of the face strip 4. Also, the strips 4 and 5 are each provided with a plurality of 75 glove fastener elements 7 which are spaced longitudinally thereof, as shown in Fig. 1.

8 designates a plurality of strips of elastic material, designated herein as head strips, each of which is secured at one of its ends to the rear element 1 (Fig. 2) in any suitable manner, as, for instance, by being stitched thereto. The head strips 8, when the device is in use, are extended along the head of the wearer from back to front thereof in the manner illustrated in Figs. 1 and 2. At the end of each of the head strips 8 opposite to the end thereof which is secured to the rear element 1, said head strip is provided with an element of a glove fastener 9, said glove fastener element being 85 adapted to engage one of the glove fastener elements 7 secured to the strips 4 and 5 to attach said head strips 8 to said face strips 4 and 5.

90 The combs C already referred to are 100

supported by the strips of elastic material or head strips 8, each of said combs being provided adjacent to its opposite ends with pairs of apertures 10 through which one of the head strips 8 passes in the manner illustrated in Fig. 3. It is obvious, in view of the arrangement of the combs C on the strips 8, that said combs may be adjusted longitudinally of said strips, during which adjustment said strips will be drawn through the apertures 10 in one or the opposite direction and because said strips are bent at rather sharp angles at the points where they pass through the apertures said combs will remain in any position with respect to the strips to which they are adjusted.

In the use of my improved hair-waving device, the appliance B is arranged upon the head of the person whose hair is to be waved in the manner illustrated in Figs. 1 and 2, and the combs C are inserted into the hair in a manner to cause the hair between said combs to be puffed outwardly or waved, as shown in Fig. 1. If desired, as already explained, the combs C may be adjusted longitudinally of the head strips 8 to properly position said combs with respect to the head of the user of the device, and also the ends of the strips 8 at the face of the wearer may be adjusted with respect to the strips 4 and 5 by shifting the glove fastener portions 9 at said ends of said strips 8 from one to the other of the glove fastener portions 7 arranged on said strips 4 and 5.

It is obvious, in view of the construction of the improved device disclosed herein, and also because of the manner in which same is applied to the head of a user thereof, that said device may be worn with the minimum discomfort, whereby the use of said device at night while the wearer is asleep is entirely feasible, and because the strips 2, 4, 5 and 8 are formed of elastic material the appliance B may adjust itself to the head of the wearer.

While I have stated herein that certain of the strips comprising the appliance B are formed of elastic material, this is not absolutely essential, for if desired all of the strips forming the appliance B may be formed of non-elastic material. Also, while I state herein that the fastening devices which are employed to attach the strips 8 to the strips 4 and 5 are glove fasteners, it is obvious that other and different fastening devices may be employed for this purpose.

I claim:

1. A hair-waving device comprising an appliance formed of a plurality of strips of material and adapted to be fitted upon the head of a user of said device, and a plurality of combs supported by said appliance and arranged in a manner to permit insertion thereof into the hair of said user of the

device, said combs being provided with apertures through which certain of said strips of material comprising said appliance pass whereby said combs may be adjusted longitudinally of said strips of material.

2. A hair-waving device comprising an appliance formed of a plurality of strips of material and adapted to be fitted upon the head of a user of said device, and a plurality of combs supported by said appliance and arranged in a manner to permit insertion thereof into the hair of said user of the device, said combs being provided with apertures through which certain of said strips of material comprising said appliance pass whereby said combs may be adjusted longitudinally of said strips of material, and end portions of said strips of material by which said combs are supported being adjustable with respect to associated portions of said appliance.

3. A hair-waving device comprising an appliance adapted to be fitted upon the head of a user of the device, said appliance comprising a rear element, a neck-encircling member, a pair of face strips secured to said neck-encircling member and arranged to be extended upwardly at opposite sides of the face and passed across the forehead of the wearer of the device, attaching means for securing said face strips together at the forehead of the wearer of the device, head strips arranged for extension over the head of the wearer of the device from said rear element to said pair of face strips, and combs supported by said head strips and adapted for insertion into the hair to be waved.

4. A hair-waving device comprising an appliance adapted to be fitted upon the head of a user of the device, said appliance comprising a rear element, a non-elastic neck-encircling member, a pair of elastic face strips secured to said neck-encircling member and arranged to be extended upwardly at opposite sides of the face and passed across the forehead of the wearer of the device, attaching means for securing said face strips together at the forehead of the wearer of the device, elastic head strips arranged for extension over the head of the wearer of the device from said rear element to said pair of face strips, and combs supported by said head strips and adapted for insertion into the hair to be waved.

5. A hair-waving device comprising an appliance adapted to be fitted upon the head of a user of the device, said appliance comprising a rear element, a non-elastic neck-encircling member, a pair of elastic face strips secured to said neck-encircling member and arranged to be extended upwardly at opposite sides of the face and passed across the forehead of the wearer of the device, attaching means for securing said

face strips together at the forehead of the wearer of the device, elastic head strips arranged for extension over the head of the wearer of the device from said rear element to said pair of face strips, and combs supported by said head strips and adapted for insertion into the hair to be waved, said combs being adjustable longitudinally of said head strips and end portions of said head strips being adjustable with respect to 10 said face strips.

In testimony that I claim the foregoing I hereunto affix my signature.

ALICE W. CULVER.
